UNITED STATES PATENT OFFICE

HANS I. HOHLT, OF SANTO DOMINGO, DOMINICAN REPUBLIC

AUTOMATICALLY CONTROLLED TOY BOAT

Application filed January 31, 1929. Serial No. 336,472.

This invention relates to direction controlling means for moving objects, such as boats, or vehicles moving on land or in air. While this invention is particularly intended for use in connection with toys, it will be understood that it is not to be restricted thereto.

One object of this invention is to provide a device of the character described, having improved wind operated means to control the course of a boat or other vehicle.

Another object of the invention is the provision of a device of the nature set forth, including improved means controlled by the wind and serving to keep the boat in a straight path.

Another object of the invention is to furnish a device of the type mentioned, comprising means actuated by the wind and operating with a rudder to steer the boat through a predetermined angle after the boat has covered a given distance.

A further object of the invention is to provide a device of the nature specified in which the turning thereof to the right or left may be predetermined, and which is simple in construction, comprises a minimum number of parts, is easy and reliable to operate, and efficient in use to a high degree.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference characters through the several views.

In the drawings:

Figure 1 is a fragmentary view in elevation showing the invention applied to a boat.

Fig. 2 is a top plan view of same.

Fig. 3 is an end rigid view in elevation with parts in section showing details of invention.

Fig. 4 is an enlarged fragmentary view in elevation of details of the control means, parts being in section.

Fig. 5 is a top plan view of the same. Fig. 6 is a diagrammatic view illustrating the steering of a boat, and showing the vane and rudder thereof in different steering positions.

Fig. 7 is a diagrammatic view showing the operation of the steering means to keep a boat on a straight course.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, are submitted merely as showing the preferred exemplification of the invention.

Generally described, this invention provides means operated by the wind for controlling the direction of an object that is driven by the wind or is self propelled. If this object should be a boat, then the means referred to actuates the rudder; if a land vehicle, the steering wheels, and if an air vehicle, the rudder.

The said means includes a vane whose direction is initially co-ordinated with that of the wind so that the vane is in equilibrium. Should the object accidentally move off a straight line course, the vane is then at an angle with the wind, and is moved thereby into the direction of the wind. In course of executing such movement, the vane steers the object back to a straight course in the predetermined direction. The means referred to is applicable to all types of vehicles mentioned.

The vane is also adapted to steer the object, being swingable through an angle of 180° to lie with its free edge opposed to the wind. This swinging movement occurs after the object, or boat has traveled a given distance, and the means for causing such movement of the vane may be of any feasible character. At any rate, the vane is moved by the wind, and accordingly moves the rudder to steer the boat.

- boat. When the latter has completed a turn of 180° , the previous movement of the vane through an equivalent angle is counteracted, so that the vane will then lie in equilibrium, with the fixed end thereof toward the wind, as initially arranged. The boat will then again proceed in a straight line. This steering device will be found to be of particular utility also for objects moving in the air.
- 10 It may be desired to predetermine the direction of steering of the boat, as for instance, in the racing of toy sailboats, where in order to simulate a natural appearance, certain of the boats ought to turn to port and others to starboard. For this purpose the vane may be offset from its axis, so as to turn either to one side or to the other side thereof in the direction in which it is offset.
- 15 Referring in detail to the drawings, 10 denotes a device embodying the invention. The same includes the poop 11 of a boat 12 to which is secured a frame 13 in alinement with the keel of the boat. The latter may be made separately for attachment to any existing boat. Said frame includes a pair of vertically spaced bars 14, 15, which are secured to the boat in any suitable manner, as shown at 16, 17. Interconnecting said bars 14, 15 are a plurality of vertical members 18, 19, which are spaced from one another, thus constituting what is in the nature of a box structure. The frame is formed with end projecting portions 20, 21, in which is journaled a vertical shaft 22, whereon is mounted a rudder 23. In the upper and lower members 14, 15 are a pair of central alined bearings 24, 25, in which is journaled a vertical shaft 26 carrying a rotor 27. The latter is of any suitable type, though the rotor shown, and which is specifically described in my Patent No. 1,656,485 dated January 17th, 1928, is preferably employed.
- 20 On the member 14, are a plurality of additional bearings 28, 29 and 30 in which are journaled spindles 31, 32 and 33. The first of these carries a gear 34, and each of the others carries a gear 35 and a pinion 36. On the upper end of the rotor shaft 26 is a pinion 37. The several gears and pinions intermesh to form a gear train for a purpose hereinafter more particularly set forth.
- 25 The frame 13 supports thereon a bracket 38 of U-form, the arms whereof constitute bearings 39, 40, in which is journaled a vertical shaft 41. A pair of intermeshing gears 42, 43, of equal size are mounted on the shafts 41 and 22, respectively. The shaft 41 is movable in its longitudinal direction to disengage the gears 42, 43 and permit reengagement of the same on lowering the shaft 41, at a different angular relation with respect to rudder shaft 22. To limit the upward movement of the shaft 41, a stop 44 is provided at the lower end thereof.
- 30 On its upper end, the shaft 41 fixedly carries a bracket 45 upon which is mounted a vane
46. The bracket 45 is mounted on the shaft 41 in any suitable manner, as for instance, by being threaded thereinto at 47, and secured by a locknut 48. The bracket includes a pair of upward extending spaced arms 49, 50 through which passes a pin 51. The vane 46 is provided with a projecting portion 52 engaging the pin 51 and thus supporting the vane. A coil spring 53 takes around the said pin, and has one end thereof extending into a hole 54 in the bracket, while the other end thereof is secured to the vane at 55. A cord, or other tension member 56, engages the vane at 57 and passes downward through eyes 58, 59 on the shaft 41, and from the latter to a post 60 on the gear 34, to be described hereinafter.
- 35 The bracket 45 is so related to the shaft 41 as to be offset laterally therefrom. Accordingly the hole 47 in the said bracket is at one end thereof, as may be readily seen in Fig. 2. At its other end, the bracket 45 has a lug 61 which has a similar threaded hole 62. The vane 46 is seen to be substantially centrally positioned between the holes 47 and 62, so that, when the mast 41 is screwed into hole 47 the vane is to the right of the keel, of the boat, looking from aft to forward; when the mast is screwed into hole 62, the vane is at the opposite side of the keel. In each case it is offset an equal distance. It is thus seen that provision has been made for rapidly moving the vane, to one side or the other of the shaft 41, to predetermine the direction of steering of the boat.
- 40 The gear 34 is provided with a plurality of angular openings 63 which are circularly arranged about the axis of the said gear. The said post or pin 60 has a shank 64 to snugly fit detachably into one of said openings. A cylindrical body 65 surmounts the shank 64, said body having a notch 66 at one side thereof, and having an opposite bevel or cam surface 67. With the notch 66 facing in a direction away from the shaft 41, the cord 56 takes around the pin 60 at the said notch, by means of a loop 68 in the cord. The latter exerts a downward tension on the vane 46, which opposes the spring 53, and retains the vane in the position shown in Fig. 1.
- 45 The operation of the device 10 will now be clearly apparent. Assume that the wind comes in the direction of the arrow *a* in Fig. 2, and it is desired to have the boat sail a straight course. The rudder 23 is placed in alinement with the keel of the boat. Then the shaft 41 is lifted, raising the gear 42 and causing the same to unmesh with the teeth of the gear 43. The cord 56 may be released from the pin 60 to permit the shaft 41 to be raised as stated, or there may be sufficient flexibility for this purpose in the spring 53. With the gears 42, 43 disengaged, the shaft 41 is turned until the vane 46 lies substantially in the direction of the wind. The shaft

41 is then lowered to cause the gears 42, 43 to engage. Thereafter the pin 60 is placed in a proper opening 63 in the gear 34 and with the cord 56 in engagement therewith.

5 The choice of the opening 63 as above set forth, is determined by the following considerations. The gear train is designed for a given speed reduction, for example, that the rotor 27 make 10,000 rotations to cause 10 one rotation of the gear 34. Thus the rotor will make 5,000 turns to move the gear 34 through an angle of 180°. If the pin 60 be placed diametrically opposite to the shaft 41, the cord 56 will remain engaged with said 15 pin until the gear 34, and consequently, the pin 60, has made a turn of substantially 180°, at which time the loop 68 of the cord will disengage the said pin by being outside the said notch 66 and sliding upward along the 20 cam 67. Now, by initially placing the pin 60 at various angular positions on the gear 34, the number of rotations necessary of the rotor 27 to cause the cord 56 to be released can be increased or decreased.

25 The rotor 27 turns in a constant direction, and the speed thereof may be governed by various factors including the relative speed as between the boat and the water, though, where the boat is used on still water, the 30 time at which the cord is released will be substantially a function of the distance traveled by the boat

Now assume that the boat is for any reason thrown out of a straight course as shown in 35 Fig. 7. The vane moves substantially into the direction *b* of the wind indicated by arrow *c*, and by means of gears 42, 43 moves the rudder 23 in an opposite direction *d*, thus returning the boat to its initial course. This 40 operation is the same regardless of the nature of the factor that throws the boat off its course, or of its direction.

After the boat has traveled a substantially predetermined distance in a straight line, 45 with a corresponding number of rotations of the rotor 27, the cord 56 will be released as hereinbefore stated, and the spring 53 will throw the vane 46 in an upward direction and through an angle of 180° in a vertical plane 50 into the position shown in dotted lines in Fig. 3. This initiates the steering of the boat as shown in Fig. 6. In this figure, the arrows *e* indicate the direction of the wind. The boat 12 is traveling from right to left as 55 indicated by arrow *f*, with its rudder 23 set in line with the keel, and its vane 46 lying substantially in the direction of the wind. When the boat 12 reaches the position indicated by the boat 12*a*, the vane 46 moves in 60 the vertical plane through an angle of 180° and occupies the position of a vane 46*a*. Since the free edge of the vane is toward the wind, the latter begins to turn the vane. The direction of the turning of the vane with its 65 shaft 41, will in this particular instance, be

clockwise, due to the offset of the vane from the axis of the shaft, as set forth in connection with the description of the bracket 45. The vane moves the rudder in a counterclockwise direction, causing the boat 12*a* to steer 70 to starboard. Certain of the positions that the boat progressively assumes as it steers completely around are indicated at 12*b* to 12*c*. The wind acts continuously on the vane, causing the rudder to be gradually deflected, while 75 the boat is simultaneously steering. Thus the speed of steering may continually increase up to a position approximately at 12*d* where the vane 46*d* may be substantially in alignment with the wind, while the rudder 23*d* is 80 at an angle with the keel. As the boat moves from 12*d* to 12*e*, the wind will retain in its direction the vane 46*d*, i. e., the vane will move with respect to the boat in a counterclockwise direction. This will cause the rudder 23*d* to move in a clockwise direction. In position 12*e*, the rudder is again in alignment 85 with the keel of the boat, and the vane, of course, lies in equilibrium in the direction of the wind. The boat has thus substantially 90 reversed its direction, and is traveling as shown by arrow *g*.

When it is desired that a race be run between a plurality of toy boats, then, in order to simulate a perfectly natural appearance in 95 the steering of the boats, certain of the boats ought to turn to port and others to starboard. This is accomplished by adjusting the bracket 45 to cause the shaft 41 to be received in the hole 47 or in the hole 62, or, in other words, 100 the direction of offset of the vane 46 from the shaft 41 is varied, and therefore the direction of initial turning of the vane in position 12*a*, and consequently the direction of steering of 105 the boat is predetermined.

I claim:

1. A device of the character described, including a movable object, steering means for the object, and wind actuated means to operate the steering means to cause the object to 110 travel a substantially constant course for a substantially predetermined distance, a motor, and operating means actuated by the motor along a portion of the path of travel of the object, said motor causing the operating means to steer the object automatically after a predetermined run of the object, said operating means including a tension member and a spring released thereby to move the steering means. 115

2. A device of the character described, including a movable object, steering means for the object, and a wind actuated vane operating the steering means to keep the object on a substantially constant course as long as the wind is constant, and means to automatically move the vane through a predetermined angle with respect to the wind to cause the vane to steer the object. 125

3. A device of the character described, in- 130

cluding a movable object, steering means for the object, and a wind actuated vane operating the steering means to keep the object on a substantially constant course as long as the wind is constant, and a member rotating as a result of the movement of said object, said member holding the vane until having made a given number of revolutions, when said member releases the vane to cause the same to move through a predetermined angle with the wind after making a given number of rotations, said member subsequently releasing the vane, said vane actuating the rudder to steer the object.

15 4. A device as set forth in claim 3, wherein said rotatable member coacts with the vane to permit the same to move through an angle of substantially 180° causing the object to steer completely around in the opposite direction.

20 5. A device as set forth in claim 3, wherein the vane is mounted for swinging movement through an angle of 180° and in a vertical plane, to completely steer said object upon release by said rotating member.

25 6. A device as set forth in claim 3, wherein automatic means is provided tending to move the vane through the angle referred to, said rotating member holding the vane in initial position, said rotating member releasing the vane, as set forth, to cause the automatic means to move the vane.

30 7. A device as set forth in claim 2, wherein the vane is mounted for movement about a vertical axis in offset relation thereto in one or the opposite direction according as the object is to steer in one or the opposite direction.

35 In testimony whereof I affix my signature.
